C. D. BONSALL

CARLINE REINFORCEMENT AND LOAD LIFTING ATTACHMENT

Filed Jan. 14, 1927

Inventor
Charles D. Bonsall

Attorney

UNITED STATES PATENT OFFICE.

CHARLES DAVID BONSALL, OF NEW KENSINGTON, PENNSYLVANIA.

CARLINE REINFORCEMENT AND LOAD-LIFTING ATTACHMENT.

Application filed January 14, 1927. Serial No. 161,093.

In some railway freight cars the roof structure comprises carlines spanning the distance between the opposite side plates with metallic roof sheets spanning the distance between the adjacent carlines. These roof sheets are sometimes secured to the carline, making what is known as a rigid all-steel roof, and sometimes positioned loosely between the carlines, making what is known 5 as a flexible all-steel roof. In such types of roofs the bottoms of the carlines are substantially flush with the bottoms of the roof sheets, thus obtaining a flat interior surface, so that it is frequently impossible to secure 10 a rope or hook to the carline, or, in fact, to any other part of the roof, therefore, it is difficult and cumbersome to move heavy 15 loads into, out of or around in the car.

My invention resides in reenforcing all or 20 some of the carlines of such an all-steel car roof by means which also constitute a support for load lifting devices and comprises means for attachment of such device.

An object of the invention is to provide a 25 pair of web plates to strengthen the carline and to provide a member which forms a splice plate to connect the web plates and form a unitary beam of the carline, web plates and member, which member also has 30 means integral therewith for attaching load lifting devices.

The end plate is the end carline of a railway car for all intents and purposes of this invention, therefore, no distinction is made 35 in the claims herein.

In the drawings:

Fig. 1 is a partial cross section of a railway car with my invention applied thereon.

Fig. 2 is an enlarged section showing the 40 connection of the web plates and associated parts.

Fig. 3 is a section on line 3—3 of Fig. 2.

Fig. 4 shows how the two piece web plate is cut from a rectangular plate.

Fig. 5 shows a different roof and a modified form of my invention.

Fig. 6 is a section on line 6—6 of Fig. 5.

Fig. 7 shows the invention applied to a flexible all steel roof.

Fig. 8 is a section on line 8—8 of Fig. 7.

In the form illustrated the roof comprises roof sheets 2 which span the distance between the opposite side plates 3 and are secured thereto. These sheets have upstanding flanges 4 at their adjacent margins and an inverted U-shaped carline 5 covering and embracing the flanges adjacent the roof sheets. In order to strengthen any carline to which it is desired to attach a load lifting device I provide a pair of vertical web plates 7 positioned between the roof flanges and attached to the carline 5 on opposite sides of the center line of the car. These plates 7 must be relatively narrow adjacent the side plate at 8 in order not to reduce the inside height of the car but they must be relatively wide adjacent the center of the car so as to project below the roof sheets far enough to accommodate the rivets 9 which secure them to a splice member. These web plates are preferably made from a rectangular plate by cutting it diagonally, as shown in Fig. 4. The web plates 7—7 on the opposite sides of the center line of the car are connected by a splice member 10 which may be a flat plate, but I prefer to make it of a U-section 11, as shown particularly in Fig. 3. This splice member is provided with an aperture 12 through which the hook or chain of a load lifting device may be passed, and in order to position this aperture as near the underside of the roof as possible, I prefer to clip off the corners of the web plates at 13 which also reduces the height of the splice, thereby maintaining the maximum inside height of the car.

I prefer the U-shape splice member 11 because it reduces the number of rivets (9) required by putting them in double shear. Furthermore, it increases the bearing area of the bottom of the aperture 12 which engages the rope or hook of the load lifting device, and, thirdly, the upper flanges 15 of the U-shape splice prevents it from tearing out under stress, either in service or process of manufacture.

Figs. 5 and 6 show my invention applied to another roof wherein the walls 20 of the carline 21 are spaced further apart and the adjacent roof sheet flanges 22 are secured to

the carline but not to each other. In these figures also I have shown a splice 23 formed by a rolled T section with its lower flanges 24 curved upwardly forming integral means for the attachment of hooks or ice tongs of a load lifting device. These lower flanges also increase the strength of the splice. The splice member may be provided with an aperture 25.

10 Figs. 7 and 8 show my invention applied to a flexible all steel roof wherein the roof sheets 30 and their flanges 31 are spaced apart from the carlines 32 and covered by a cap 33 usually secured to the carline. There is free movement between the roof sheets on opposite sides of the carline as well as between the roof sheets and the cap. In this construction I have shown a splice formed by two oppositely disposed flat members 34 provided with registering apertures 35.

It is understood that any of the splice members or means for attaching a load lifting device described herein or any construction similar thereto may be used with any 25 of the roofs shown herein or any similar roof thereto and still come within the scope of this invention.

The pitch of the roof varies in different cars or the variation in the depth of the carline may be different, therefore, in some cases it may be that the beam (formed by the combination of the carline, web plates and splice plate) is relatively weak between the end of the splice and the side plate so in order to provide more strength between these points I provide a flange 40 at the lower margin of the web plate, which flange does not decrease the inside height of the car. This flange may increase in width from adjacent the splice (41) toward the side plate 3 in proportion to its decrease in vertical width so that it may be made from a rectangular plate.

45 My co-pending application No. 93,155, filed March 8, 1926, shows a pair of web plates used to reinforce a carline, but the invention covered by this application for patent is an improvement thereon, as the single member used to connect the oppositely disposed web plates also provides integral means for attaching a load lifting device.

I claim:

1. In a railway car, the combination of 55 roof sheets having upstanding flanges at their adjacent edges, an inverted U-shaped carline covering the flanges of adjacent roof sheets, a pair of vertical plates positioned between the roof flanges and attached to the carline on opposite sides of the center line of the car which extend below the roof sheets, and a splice member securing the vertical plates together provided with an aperture for the attachment of a load lifting device.

2. In a railway car, the combination of

60 roof sheets having upstanding flanges at their adjacent edges, an inverted U-shaped carline covering the flanges of adjacent roof sheets, a pair of vertical plates positioned between the roof flanges and attached to the carline on opposite sides of the center line of the car which extend below the roof sheets, and a splice member securing the vertical plates together provided with integral means for the attachment of a load lifting device.

3. In a railway car, the combination of 65 roof sheets having upstanding flanges at their adjacent edges, an inverted U-shaped carline covering the flanges of adjacent roof sheets, a pair of vertical plates positioned between the roof flanges and attached to the carline on opposite sides of the center line of the car which extend below the roof sheets, a U-shaped splice member embracing 70 the vertical plates and securing them together, said member provided with an aperture for the attachment of a load lifting device.

4. In a railway car, the combination of 75 roof sheets having upstanding flanges at their adjacent edges, an inverted U-shaped carline, a pair of vertical plates positioned between the roof flanges and attached to the carline on opposite sides of the center line of the car which extend below the roof sheets, each of said plates having a flange 80 at its lower margin, and a splice member securing the vertical plates together provided with an aperture for the attachment of a load lifting device.

5. In a railway car, the combination of 85 a carline, a pair of vertical plates attached to the carline on opposite sides of the center line of the car which extend below the carline, and a splice member securing the vertical plates together provided with an aperture for the attachment of a load lifting device.

6. In a railway car, the combination of a 90 carline, a pair of vertical plates attached to the carline on opposite sides of the center line of the car which extend below the carline, and a splice member securing the vertical plates together provided with integral means for the attachment of a load lifting device.

7. In a railway car, the combination of a 95 carline, a pair of vertical plates attached to the carline on opposite sides of the center line of the car which extend below the carline, and a splice member securing the vertical plates together provided with an aperture for the attachment of a load lifting device.

8. In a railway car, the combination of a 100 carline, a pair of vertical plates attached to the carline on opposite sides of the center line of the car which extend below the carline, a U-shaped splice member embracing 105

the vertical plates and securing them together provided with an aperture for the attachment of a load lifting device.

9. In a railway car, the combination of a carline, a pair of vertical plates attached to the carline on opposite sides of the center line of the car which extend below the cor-

line, each of said plates having a flange at its lower margin which increases in width toward the side plates, and a splice member ¹⁰ securing the vertical plates together provided with an aperture for the attachment of a load lifting device.

CHARLES DAVID BONSALL.
